UNITED STATES PATENT OFFICE.

THOMAS C. JOHNSON, OF NEW HAVEN, CONNECTICUT, ASSIGNOR TO WINCHESTER REPEATING ARMS CO., OF NEW HAVEN, CONNECTICUT, A CORPORATION.

BOLT-ACTION GUN.

1,355,673.

Specification of Letters Patent.

Patented Oct. 12, 1920.

Application filed May 22, 1920. Serial No. 383,354.

To all whom it may concern:

Be it known that I, THOMAS C. JOHNSON, a citizen of the United States, residing at New Haven, in the county of New Haven 5 and State of Connecticut, have invented a new and useful Improvement in Bolt-Action Guns; and I do hereby declare the following, when taken in connection with the accompanying drawings and the characters of reference marked thereon, to be a full, clear, and exact description of the same, and which said drawings constitute part of this application, and represent, in—

Figure 1. A broken view in side elevation 15 of a bolt-action gun provided with a filler-block in accordance with my invention.

Fig. 2. A similar, but less comprehensive view, showing the rear end of the receiver as it appears when the filler-block is removed preparatory to the installation of a leaf-sight mount or a telescope-sight mount.

Fig. 3. A detached view in rear elevation of the receiver which is stripped except for my improved filler-block.

Fig. 4. A detached plan view of the filler-block.

Fig. 5. A side view thereof.

Fig. 6. A view thereof in rear elevation.

My invention relates to an improvement 30 in that class of bolt-action guns providing for the installation on the receiver of the arm and close to the eye of the user thereof, at the pleasure of the user, of a leaf-sight or a telescope-sight; the object of my present invention being to provide for filling the cut in the rear end of the receiver when both of these sights are replaced by a sporting-sight on the barrel of the arm.

With these ends in view, my invention 40 consists in a bolt-action gun having its receiver formed with an upwardly and laterally opening cartridge-receiving and ejection opening and with a transverse mounting-slot located immediately in the rear of the said opening, and a filler-block provided 45 at its forward end with a dovetail rib for insertion into the slot and provided with a rearward extension arranged to overhang the rear end of the receiver, and formed at the right hand of its overhanging end with a slot for the clearance of the bolt-handle when the same is lifted into its unlocked position.

In carrying out my invention, as herein 55 shown, the receiver 2 of the gun is formed

with the usual upwardly and laterally opening cartridge-receiving and ejection opening 3. Immediately to the rear of this opening, the upper face of the receiver is formed with a transverse dovetail-slot 4 for the reception of a dovetail-rib 5 depending from and arranged transversely to the longitudinal axis of a filler-block 6, the rear end of which is formed with an extension or overhang 7 which overhangs the rear end of the receiver by something over a third of the length of the entire block. The extension or overhang 7 of the filler-block is formed on its right hand side with a clearance-cut 9 for the clearance of the bolt-handle 10 when the same is lifted into its unlocked or horizontal position. The gun is also provided with a bolt 11 furnished at its rear end with a bolt-head 12, in front of which the handle 10 is mounted; but the detailed construction of the gun may be varied as desired, since my invention is directed solely to its provision with a filler-block to take the place of the mounting-blocks of leaf and telescope sights.

The filler-block as shown in the drawings has all of its corners and edges which are exposed when the block is in position on the gun, rounded, so as to prevent scratching other objects and to prevent unnecessary wear and possible tearing of the gun-case by sharp projections.

By means of my filler-block, the user may restore the receiver to substantial integrity of form and appearance when he 90 does not desire to use either of the two sights provided for use at the rear end of the receiver, close to the eye. Without this block, he must leave the gun in an apparently mutilated and unsightly condition 95 when he is not using either of the receiver-sights referred to. Moreover, when the gun is put in a gun-case or packed in a trunk, or in a suit-case or similar package, the sharp corners of the rear upper surface of the receiver would be very damaging without the round-cornered filler-block to cover them.

I claim:

In a bolt-action firearm, the combination 105 with a receiver having an upwardly and laterally opening cartridge-receiving and ejection opening and a transversely arranged, undercut mounting-slot located in the upper face of the receiver at a point 110

immediately in the rear of the said opening; of a detachable filler-block provided at its forward end with a depending, transversely arranged rib for insertion into the said slot, 5 and at its rear end with an extension overhanging the rear end of the receiver, and formed on its right-hand side with a clearance-cut for the reception of the bolt-handle when the same is in its elevated position, 10 the said filler-block being of the same width

as the said receiver and having all of its outstanding corners and edges rounded off.

In testimony whereof, I have signed this specification in the presence of two subscribing witnesses.

THOMAS C. JOHNSON.
